UNITED STATES PATENT OFFICE

JOSEPH E. EVANS, OF BEDFORD, INDIANA, ASSIGNOR TO EVANS ELEVATOR EQUALIZER COMPANY, OF BEDFORD, INDIANA, A CORPORATION OF INDIANA

SUSPENSION DEVICE FOR EQUALIZING THE STRAIN ON ELEVATOR CABLES

Application filed May 16, 1929. Serial No. 363,695.

My invention relates to a device designed to connect an elevator car and a group of hoisting cables arranged to travel around a suspension pulley at the top of the elevator shaft in which the car travels up and down, and the purpose of the device is to distribute the weight of the car equally among the cables at all positions of the car in its travel, whether, because of slight variations in the 5 diameter of the cables or the depths of the 10 grooves of the suspension pulley or other causes, such as variations in the stretch of the different cables, there is some creeping of the 15 cables affecting their longitudinal relation to each other in the course of their travel, or not. The object of my invention is the provision 20 of an equalizing device employing rocking levers or bars as the equalizing members which shall function efficiently and be particularly well adapted to attain the ends in 25 view, and shall be economical to construct and be strong and simple and little liable to derangement in use. To this end I have devised and invented the suspension device 30 hereinafter described in detail, the essential elements of my invention being more particularly pointed out in the appended claims.

In the drawings, Figure 1 is what I will term an end view of the device, and fragmentary portions of the hoisting cables and 35 elevator car which are thereby connected;

Fig. 2 is a side view of the same;

Fig. 3 is a horizontal section on the dotted line 3—3 of Fig. 1; and

Fig. 4 is a bottom plan view of the device.

Like reference characters indicate like parts in all the figures of the drawings.

My novel equalizing device is designed to be secured to a pair of horizontal beam members at the top of the elevator car. These beam members, marked A—A in the drawings, may conveniently form a part of the frame work of the car and are preferably flanged at top and bottom, as illustrated. Resting 45 upon the top flanges of the beams A is ar-

ranged a guide frame, consisting of two pairs of L-shaped bracket strips 1 having upwardly extending members which are bolted together between a pair of guide plates 2—2 extending from one pair of bracket strips to the 50 other. The horizontal members of the four bracket strips are connected by clamping bolts 3 with a bottom plate 4. This bottom plate is formed with depending bearing brackets, in the present instance three in 55 number, including a central bracket 5 and outer or side brackets 6—6, and also preferably with strengthening cross-ribs 7 and 8, as illustrated in the drawings.

The guide-frame and bottom plate, 60 clamped to the beam members of the car as described, constitute the stationary frame work of the device in which the equalizing and suspension mechanism is mounted.

As illustrated, my equalizing device is designed for attaching the elevator car to a group of six hoisting cables traveling in parallel grooves of the suspension pulley (not illustrated), the number of cables usually employed, and the cables are spread in two 70 groups of three cables each, in staggered relation, the cables of one group being marked 9 on the drawings, and the cables of the other group being marked 10. Each cable 9 is connected by a bolt 11 having an anchorage 75 socket 12 with a block 13 pivotally mounted between the ends of a pair of upper equalizer bars 14—14, the other ends of such bars similarly connected with a diagonally opposite cable 10, each pair of equalizer bars thus 80 connecting a pair of cables which are adjacent each other in their travel over the suspension pulley, not shown. Centrally between each of the pairs of bars 14 is pivoted the upper end of one of three links 15, 15^a, 15^b, 85 which extend downwardly between the guide plates 2. In the present instance, and preferably, I have provided, in the spaces between adjacent links and bolted to the guide plates 2, blocks 16, which may be formed of hard 90

wood, soaked in oil, or fibre board, or metal, and which are of such dimensions as to prevent undue sidewise sway of the several associated links and cables, while not interfering 5 with the functioning of equalizing bars pivoted to their lower ends, later to be described. Each of the links is twisted slightly near its upper end to provide for the slight obliquity of the pivot bearing at that end.

10 The lower end of two adjacent links, as the links 15 and 15^a, are pivoted between the opposite ends of a pair of intermediate equalizer bars 17—17, and the centers of these bars are pivotally connected by a pair of lower 15 links 18—18 with corresponding and shorter ends or arms of a lower pair of equalizing bars or levers 19—19 which are intermediate- 20 ly mounted upon a pivot rod 20 extending through the bearing brackets 5 and 6. The longer arms of said bars or levers are pivotally connected by a second pair of lower 25 links 21—21 with the lower end of the link 15^b. The distance between the pivot centers of the shorter arms of the levers 19 is one-half that of the longer arms, whereby the strain of the four cables connected to the links 15 and 15^a just balances that of the two cables connected to the link 15^b. It is obvious that by means of the linkage de- 30 scribed each of the suspension cables will sustain an equal part of the load of the car, while permitting some variation of travel of the cables over the suspension pulley with respect to each other as the car is hoisted up 35 and lowered down in the elevator shaft by the group of cables.

While the various equalizer bars and levers and the lower links of the device as illustrated are of double or twin construction, for 40 the purpose of balancing the stresses on the pivot connections of the parts, it is obvious that the companion parts function as one, and the appended claims are intended to be construed with this understanding.

45 It is further obvious that my device is adapted to be used to suspend the counter-weight of an elevator car to the counter-weight end of the cables, and I desire my claims construed to include the application 50 of my invention to a counter-weight or other load attached to a group of hoisting cables.

I claim:

1. A suspension device for connecting an elevator car to a group of six hoisting cables 55 comprising three upper equalizer bars severally connected to pairs of adjacent cables, three upper links pivoted centrally to said equalizer bars, an intermediate equalizer bar pivoted at its opposite ends to two of said 60 upper links adjacent each other, a lower link pivoted at its upper end centrally to said intermediate bar and at its lower end to the short arm of the hereinafter mentioned lower equalizer bar, and a lower equalizer bar 65 intermediately pivoted upon the frame of

the device and having a short arm connect- 70 ed as described to said lower link and hav- ing its other and longer arm connected to the remaining one of said first mentioned links.

2. A suspension device for connecting a plurality of more than four cables to an elevator car, said device including a guide frame secured to the car a pair of upper equalizer bars each connected to a pair of adjacent cables, a pair of upper links severally pivoted 75 centrally to said pair of upper equalizing bars and slidably engaging said guide frame, an intermediate equalizer bar pivoted at its opposite ends to said pair of upper links, a lower link pivoted centrally to such intermediate equalizer bar, and a lower equalizer bar intermediately pivotally connected with the car and at one end connected to said lower link and at the other end connected to the remaining ones of said cables, the strain of 80 the cables connected to opposite ends of said lower equalizer bar being balanced.

3. A suspension device for connecting a plurality of cables to an elevator car includ- 85 ing parallel upper equalizer bars each con- nected to a pair of adjacent cables and to- 90 gether arranged to spread said cables in two groups in staggered relation, a pair of upper links severally pivotally connected to a pair of adjacent upper equalizer bars centrally there- 95 of, an intermediate equalizer bar connected at its opposite ends to a pair of adjacent upper links, a lower link pivotally connected to the said intermediate equalizer bar centrally thereof, and a lower equalizer bar intermediately pivotally connected with the car and at one end connected with said lower link and at the other end connected with cer- 100 tain cables other than the four adjacent cables connected to said intermediate equalizer bar, the strain of the cables connected to op- 105 posite ends of said lower equalizer bar being balanced.

4. A suspension device for connecting a plurality of more than four cables to an ele- 110 vator car having at its top a pair of hori- zontal beams, said device comprising a guide frame arranged on top of said beams, a bottom plate underneath said beams, clamping 115 bolts for clamping said guide frame and bot- tom plate to said beams, a pair of upper equalizer bars each connected to a pair of adjacent cables, a pair of upper links severally pivoted centrally to said pair of upper equalizing bars and slidably engaging said 120 guide frame, an intermediate equalizer bar pivoted at its opposite ends to said pair of upper links, a lower link pivoted centrally to such intermediate equalizer bar, and a lower equalizer bar intermediately pivoted upon 125 said bottom plate, and at one end connected to said lower link and at the other end connected to the remaining ones of said cables, the strain of the cables connected to opposite 130

ends of said lower equalizer bar being balanced.

5. A suspension device according to claim 2 in which said guide frame includes spaced 5 guide plates at its opposite sides and said upper links are bars arranged between said guide plates.

6. A suspension device according to claim 2 in which said guide frame includes spaced 10 flat guide plates at its opposite sides and said upper links are bars arranged between said guide plates and in which guide blocks are arranged between and secured to said guide plates between proximate faces of said links.

15 In testimony whereof, I have subscribed my name.

JOSEPH E. EVANS.
